Inventor:

Alfred P. Le Gros

UNITED STATES PATENT OFFICE.

ALFRED P. LE GROS, OF LOUISVILLE, KENTUCKY.

CAR-ROOF.

SPECIFICATION forming part of Letters Patent No. 280,635, dated July 3, 1883.

Application filed December 9, 1882. (No model.)

To all whom it may concern:

Be it known that I, ALFRED P. LE GROS, of the city of Louisville, county of Jefferson, and State of Kentucky, have invented a new 5 and useful Improvement in Roofs for Railroad Box-Cars and the Running-Board thereto Attached.

A full, clear, and exact description is given in the following in reference to the accompanying drawings.

The object of my invention is to improve the car-roof of a railroad box or freight car in the following two particulars: first, to have the wooden roof covered with canvas, 15 which is always well saturated with paint; secondly, to have the running-board fixed or attached to the ridge of the roof in such a manner that it can be removed without injuring the roof. The original object is that the roof 20 of the car be guarded from breaks, holes, or leaks of any kind.

I also accompany the application with a drawing, showing, in Figure 1, a vertical view along the side of the roof; in Fig. 2, a vertical section of the running-board; in Fig. 3, like section of the blocks on which it is to rest, with projection of adjoining part of the roof; and in Fig. 4, an end view of roof.

In order to enable those skilled in the art to 30 construct the improved car-roof with running-board, according to my invention, I now specify the same, referring to the drawings above mentioned.

Laying down the side beams and gable- 35 rafters, as usual, I lay upon them planks of convenient thickness—for which I would recommend one and one-half inch—and of convenient width—for which I would recommend six inches—running down from ridge or middle on 40 each side beyond the side beams, as is now customary. These boards are nailed down to the side beams and rafters, as usual. A in the drawings, wherever it occurs, represents such boards—say six inches wide on their lower 45 surface—with a half-rabbit cut out at each edge from their upper faces, where they meet the adjoining boards—except the two extreme boards, which have the rabbit cut in only one edge—the two half-rabbits together leaving 50 room for inserting a dovetailed stick of the form shown in the drawings. The letter B,

wherever it appears in the drawings, represents such a stick. The lower edges of the rabbit are slightly inclined downward to where the two boards meet, as shown. On 55 either side of the rabbit is a groove, (marked D in the drawings,) and a similar groove is put in each side of the dovetailed stick B. (This groove is marked E in the drawings.) The dovetailed sticks should protrude slightly—60 say one-fourth inch—above the upper surface of the boards; but this is not essential. On the upper surface of the boards, and along the inner surface of the rabbits, a thick coat of ordinary paint is laid. Over this coat of paint, 65 and fitting into the rabbits, canvas is drawn, (marked C in drawings,) and this canvas is held down by the dovetailed sticks, as shown in the first drawing. The canvas is painted also on its upper side. The object of the 70 paint on the inner side of the canvas is mainly to protect the wood from warping and the nails from rusting.

In order to construct the roof according to this method, the first board, beginning at one 75 end of the frame, ought first to be nailed down next its upper surface, and the surface of the rabbit should be painted heavily. Then draw the canvas over it, and afterward paint the lower side of the canvas where it fits into the 80 half-rabbit, as well as its upper side; then draw it into the half-rabbit. Next, the dovetailed stick is laid down, and a coat of paint put on its upper side or on the inside of the canvas joining it. Then put paint on the other side of the canvas. The next board is then laid down; but at least the inside of the half-rabbit which joins that of the first board has to be painted before the board is nailed in its place. The builder will proceed in the same order to lay down each 85 board, put on paint, draw the canvas farther, lay down the next dovetailed stick and the next board, nailing down each board when it is put in its place till he comes to the last board, which has a half-rabbit on only one 90 edge or side.

The object and effect of the inclined bases of the rabbit is to keep a reservoir of moist paint between them and the flat base of the dovetailed stick, and the same object and effect will be also subserved by the grooves in 95 the sides of the rabbit and stick.

Having thus described my invention, I claim as new and desire to protect by Letters Patent—

1. In a car-roof, the combination of canvas with the roof-boards rabbeted in their upper edges, and with dovetailed strips adapted to hold the canvas in the rabbets, substantially as set forth.
2. In a car-roof, the combination of the roof-boards, of the canvas, and of a layer of paint between the boards and the canvas, operating to keep the boards oiled, substantially as set forth.
3. In such a car-roof, the combination of

the roof-boards rabbeted in their side edges, of strips adapted to be placed within the rabbets, and of the canvas and paint, the rabbets and strips being so formed with reference to each other as to leave channels capable of retaining an excess of paint, so as to keep the canvas moist and to fill any cracks of the wood, substantially in all or any of the modes above described.

ALFRED P. LE GROS.
